C. P. WATSON,
DETONATOR FOR PROJECTILES,
APPLICATION FILED JAN. 13, 1917.

Patented Sept. 23, 1919.

UNITED STATES PATENT OFFICE

CHARLES P. WATSON, OF PHILADELPHIA, PENNSYLVANIA, ASSIGNOR TO WATSON ARMS COMPANY, INC., OF PHILADELPHIA, PENNSYLVANIA, A CORPORATION OF DELAWARE.

DETONATOR FOR PROJECTILES.

1,316,607.

Specification of Letters Patent. Patented Sept. 23, 1919.

Application filed January 13, 1917. Serial No. 142,200.

To all whom it may concern:

Be it known that I, CHARLES P. WATSON, a citizen of the United States, residing at Philadelphia, in the county of Philadelphia and State of Pennsylvania, have invented 5 certain new and useful Improvements in Detonators for Projectiles, of which the following is a specification.

This invention relates to detonators for 10 ordnance shells, it being designed particularly as a nose impact detonator to be applied to shells containing high explosive, and adapted particularly for use in field operations, although the invention is not 15 limited in its useful applications to use in connection with shells of this particular kind.

In the accompanying drawings,

Figure 1 is a central longitudinal sectional view of a detonator embodying my improvements, a small portion of the shell to which it is applied being represented, and the parts of the detonator being represented as in armed position and adjusted 25 for quick firing or detonation.

Fig. 2 is a central longitudinal section of the detonator, the parts thereof being represented in unarmed or safety position and adjusted for slow firing or a delayed 30 detonation.

Fig. 3 is a transverse sectional view of the main piece or body of the detonator, taken on the line 3, 3 of Fig. 1.

Fig. 4 is a transverse sectional view on 35 the line 4, 4 of Fig. 1.

Fig. 5 is a longitudinal sectional view of a different form of the invention from that shown in the other views.

Fig. 6 is a sectional detail view of a different form of mechanism employed for adjusting the firing pin.

Fig. 7 is an end view of the firing pin adjuster shown in Fig. 6.

In the drawings 2 indicates a shell or 40 projectile adapted to carry a charge of high explosive that is placed within the chamber 45 of the shell. It is provided with a detachable nose piece 3 that serves to close the opening into the chamber 45, at the forward 45 end of the shell. To this nose piece is secured, through screw-threaded connection 4, the body or main supporting piece 5 of the detonator, which piece is formed with a neck 6 that is screwed into the nose piece

and has a shoulder 7 that abuts against the 55 rear face of the nose piece when the parts are assembled, constituting a strong abutment at this point. The body 5 of the detonator is externally screw-threaded near its middle, as indicated at 8, to engage with the 60 shell, and its rear portion is reduced in diameter and externally screw-threaded, as indicated at 9 to provide for the attachment of the casing 10 that carries the booster charge. It is well understood that in using 65 a detonator such as here illustrated, whether placed in the front or the rear end of a shell, the casing containing the booster charge enters a recess formed therefor in the mass of high explosive constituting the 70 bursting charge of the shell 2. The casing 10 is therefore of sufficiently thin and fragile material to properly yield to the booster charge upon its being detonated or exploded. By making the casing 10 separate from the 75 body of the detonator it can be formed from a single piece of metal, its inner end being thus integral with its side walls, and hence not liable to separate therefrom under the shocks to which the detonator is exposed 80 when in service use. Furthermore, there are decided advantages in construction and manufacture incident to making the body 5 and casing 10 separate, as much shorter stock material is thus required for the detonator proper. Another advantage incident to making the casing containing the 85 booster charge separate from the body or main portion of the detonator, containing the firing and other functioning mechanism, 90 is that the booster casing may be loaded and shipped separate from the body part of the detonator; and as such part contains the fulminate of mercury or other sensitive charge, the danger of accidental and destructive 95 explosions in transit is thus reduced.

The casing 10 is preferably provided with a shoulder 12 abutting against the inner end of the body of the detonator for the purpose of taking shocks due to impact and relieving the screw threads 9. It has been also found advantageous to provide the casing with an external screw thread 11 of the same pitch and diameter as the thread 8, and adapted to directly engage with the screw-threaded part of the shell 2 when the detonator is applied thereto, particularly when this feature of the invention is used 105

in connection with a fuse or detonator adapted to be applied to the rear end of a shell, as these threads are found to support and hold the casing securely in position 5 and prevent its separation from the other parts of the detonator, as might take place should the screw threads 9 be alone relied upon for this purpose.

The body 5 of the detonator is internally 10 chambered as indicated at 23, and in this chamber is mounted a plunger 22 which is free to move to a limited extent therein. The chamber is closed at its inner end by a plate or partition 24, and between this and 15 the plunger is located a coiled spring 25 that tends to hold the plunger in its forward position, that is, toward the nose of the shell. The plunger is transversely slotted as indicated at 18, and in the slot is mounted an 20 oscillating turret 14 supported upon bearings 15 on which it is free to rock.

The turret is chambered as indicated at 18 to receive a capsule or miniature projectile 19 in which is placed the detonating charge 25 of fulminate of mercury or other sensitive explosive.

The plunger body in rear of the turret 14, and the partition 24, are perforated, the perforations in these parts being in alinement 30 with each other, their axis being preferably the longitudinal axis of the detonator. A tube 27 constituting a runway is fitted into the aperture in the rear portion of the plunger, and another runway tube 53 is secured 35 to the partition 24 in line with the said apertures. The turret 14 is adapted to be oscillated upon its trunnions or bearings 15 so that the chamber 18 therein shall aline with the apertures and runway tubes just referred to, as indicated in Fig. 1, when the 40 parts are in armed position; or shall be out of line therewith and entirely cut off therefrom, as indicated in Fig. 2 when the parts are in safety or unarmed position. The 45 parts are held positively in the latter position by a locking bolt 28 mounted in the plunger and acted upon by a spring 29 that holds it in locking position with its end in a recess formed therefor in the turret.

50 Another locking pin 58 may be employed for holding the turret positively in armed position. This locking pin is seated in a recess 59 formed in the turret, which recess is adapted to come into alinement with a 55 recess 60 formed in one wall of the plunger 22 that bounds the slot 13 in which the turret is located, when the latter comes to the position indicated in Fig. 1, that is, to armed position. The pin 58 is free to slide in the 60 recesses 59 and 60, and when the shell begins to spin, centrifugal force tends to throw the pin outward, so that when the turret rocks and the recesses 59 and 60 come into alinement the pin will be shot into the latter, locking the turret in armed position. It

will be understood that the pin is short enough to lie entirely within the recess, 59, and that it is held therein by the bounding wall of the slot 13 until the parts come to the position indicated in Fig. 1.

The turret is formed with an eccentric projection 16, adapted, when the parts are in safety or unarmed position, to occupy a seat 17 formed at the inner end of a plug 47 screwed into the forward end of the body 75 piece 5. The projection 16 is held against this seat by the action of the spring 25, and constitutes a means, in addition to the locking bolt 28, for holding the parts in safety 80 position.

In practice the turret is so made that it is balanced upon its pivotal supports 15, that is to say, any two parts thereof diametrically opposed and in a plane crossing the axis of oscillation are of equal weight, as near as 85 this may be in the manufacture of an article like the turret 14. It will be seen, however, that the disposition of the mass of the turret is such that its longest diameter is through the eccentric projection 16, so that when the 90 latter is subjected to centrifugal force of sufficient amount it will rock from the position indicated in Fig. 2 to that indicated in Fig. 1. In the former position not only is the projection 16 seated, but the capsule 19 95 containing the detonating charge is out of line with the runway leading into the midst of the booster charge, while in the latter position, the turret having turned, the capsule is in line with this runway and ready 100 to be projected along the said runway, that is to say, the detonator is in armed position. Behind the capsule is located a charge of explosive 21, such as black powder, that is 105 adapted to be fired by a cap or primer supported in the turret.

30 indicates a firing pin mounted in the plug 47 at the forward end of the detonator and arranged to engage with the cap 20 under conditions to be presently stated. 110 The firing pin is carried by a plunger 31 that is mounted in a recess 33 formed in the plug 47. A coiled spring 32 acting upon the plunger tends to retract the firing pin and hold it out of firing position, that is, so that 115 upon impact of the shell it will not act upon and fire the cap 20. The plunger 31 is provided with a contact extension 34 upon which bears an adjustable wedge or tapering plug 35. This wedge is provided with a screw-threaded portion that is adapted to engage with either of two internal screw threads, 36 and 37, cut in the walls of a recess 51 formed in the nose piece 3. When the plug is engaged with the outer screw 120 thread, 36, the tapering portion or point of the wedge is opposite the projection 34 and the plunger 31 being then free to be moved by the spring 32 is forced forward and the firing pin 30 is retracted. When, however, 125

the plug is caused to engage with the screw thread 37 the expanded or wider portion of the wedge is brought opposite the projection 34, and this forces the plunger 21 forward, compressing the spring 32 and projecting the firing pin into active or armed position, as indicated in Fig. 1. The recess 51 is open from the outside, permitting access to the head of the plug 35 in which is formed a kerf 52 adapted to receive the end of a screw driver, by which it may be manipulated.

In Figs. 6 and 7, I illustrate a different form of wedge or tapering plug for controlling the position of the firing pin. The wedge or plug, in this form of the invention, is externally grooved, as indicated at 62, and split spring rings 63, lying partially in the grooves 62 and partially in grooves formed in the wall of the recess 51, hold the wedge or plug in place. There are preferably two split spring rings 63 and two grooves formed in the plug or wedge, in the construction illustrated in these views. When the wedge is adjusted to the position indicated in Fig. 6, the firing pin 34 then being in unarmed or safety position, the outer ring 63 lies partially in the first or inner groove 62, while the inner ring is in engagement with the smooth, cylindrical portion of the wedge. Under these conditions, the wedge is held with sufficient security to prevent any accidental displacement thereof. When it is desired to arm the detonator, the wedge is driven inward, the elasticity of the springs permitting it to move past them, until the two grooves become respectively opposite the two rings, when they will contract and enter the grooves in the wedge, securely locking it in the position corresponding to the position of the wedge illustrated in Fig. 1, and holding the firing pin armed.

The inner end of the plug 47 is shaped to form a firing rim 38 which is preferably concentric with the firing pin 30, and is adapted to engage with and explode a second cap or primer 39 seated in the turret and arranged to ignite a powder train located in a channel 40 formed in the turret 14. This channel communicates with the inner end of the chamber 18 in which is seated the capsule 19.

The capsule is provided at its forward end with a cap 50 that is adapted to be engaged by a firing pin 46 carried at the inner end of the runway tube 53. The detonator has now been sufficiently described to warrant its operation being set forth. After the shell 2 has been loaded the detonator, with the nose piece attached, is applied, being screwed into the forward end of the shell. The parts of the detonator are then in the positions indicated in Fig. 2, so far as the turret is concerned. Upon the

discharge of the gun the violent impulse given to the shell causes the plunger 22 to set back, compressing the spring 25. This withdraws the projection 16 from the seat in which it was resting. At the same time 70 the locking bolt 28 is set back, freeing the plunger so that it may be rocked upon its trunnions 15 under the influence of centrifugal force. The parts are so related that centrifugal force, due to the rotation of 75 the shell imparted by the rifling of the gun, acts to rock the turret, bringing it to the position indicated in Fig. 1 at about the time or shortly after the shell leaves the muzzle of the gun and before acceleration 80 of the shell in its flight has ceased, which acceleration insures that the plunger 22 and the locking bolt 28 shall be maintained in their set back positions just referred to. Upon the shell attaining its maximum 85 velocity the spring 25 acts to set forward the plunger, the turret now being in the position shown in Fig. 1, that is, with the axis of the recess in which is situated the capsule carrying the detonating charge in line with 90 the runway tubes 27 and 53. The turret is shaped with a straight face 54 that, coming into engagement with the inner wall of the plunger body 5, limits the oscillation 95 of the turret and arrests it in proper armed position. The turret is provided with a shear pin 48 that enters a recess 49 formed in the inner wall of the detonator body 5 when the turret is rocked into armed position. As the plunger and the turret which 100 is carried thereby are moved forward by the spring 25, during the flight of the shell, the shear pin 48 reaches the end of the recess 49 where it is stopped and positively arrests further forward movement of the plunger 105 and turret, as indicated in Fig. 1. The movable parts now come to rest relative to each other, in position arming the shell. If it be desired that the shell shall be exploded instantly upon impact, the plug will 110 have been adjusted to the position indicated in Fig. 1 immediately before the shell was loaded in the gun, forcing the firing pin forward and into position to engage with the primer 20. This can be safely done, 115 because the parts are then in the unarmed, safety, position indicated in Fig. 2. Upon impact of the shell the plunger and turret set forward, shearing the pin 48, and the primer 20 is carried forcibly into engagement with the firing pin 30, which is backed and held rigidly in firing position by the adjustable plug or wedge piece 35. The explosion of the primer 20 ignites the black powder charge, 21, which fires the capsule 120 or miniature projectile from its seat and along the runway through the partition 24. Upon reaching the end of this runway, the capsule then being in the tube 53 and in the midst of the detonating charge in the casing 125 130

10, the cap 50 at the forward end of the capsule comes into engagement with the firing pin 46 which explodes the cap, and that in turn sets off the detonating charge carried by the capsule. This causes the detonation of the booster charge, and that in turn causes an explosion or detonation of the main charge carried by the shell. Since the capsule fits the aperture 26 through the partition 24 and the bore of the tube 53 quite closely, the body of air confined in front of the capsule would be compressed very highly were the tube 53 air-tight, possibly highly enough to offer sufficient resistance to stop the capsule before it reached the firing pin 46, or to so reduce its velocity that the engagement with the firing pin 46 would not be sufficiently forcible to cause the cap 50 to be fired. I therefore prefer to perforate the inner end of the tube 53, as indicated at 42, and to cause the end of the tube 53 to register with or enter a tube 41 secured, as by a bolt 43, to the inner end of the casing 10. With this arrangement the air passes from the tube 53 before the moving capsule and into the tube 41, and the size of the latter is sufficient to take care of the entire body of air moved without causing serious compression thereof. When it is desired that the bursting of the shell shall be somewhat delayed after impact, as for instance to permit it to penetrate the earth to a considerable distance before exploding, the adjustable plug 35 is left in the position indicated in Fig. 2. The firing pin is then retracted through the action of the spring 32. Upon impact of the shell the cap 20 is not exploded because the firing pin is retracted, but the cap 39 is exploded by the engagement of the firing rim 38 therewith. This ignites the powder train located in the groove 40, which finally ignites the powder charge 21, whereupon the operations already described take place. It will be understood that when the parts are arranged for quick firing upon impact the cap 39 is exploded at the same instant as is the cap 20, but before the powder train is consumed the shell has burst and hence this more slowly acting means of firing may be ignored, as its effect is *nil*, unless the cap 20 should fail to function.

44 indicate passages within the detonator leading to the recess 51 in the nose of the projectile. If from any cause any one, or even all, of the explosive charges carried by the turret should become accidentally ignited or detonated, no serious injury would result to the detonator beyond rendering it dead, provided the turret occupied its normal safety position. The walls of the detonator body 5 are sufficiently strong, especially when reinforced by the walls of the shell into which the detonator is placed, to resist 60 pressure due to explosions or detonations

such as just supposed, and the passages 44 make provision for permitting expansion of the gases incident to accidental explosions, in a direction away from the booster charge. The expansion of the gases through these 70 passages and the loss of heat, which would be conducted away by the surrounding metal, would hence reduce pressures below a dangerous point.

In Fig. 5 I have shown an arrangement 75 of the parts of the detonator different from that embodied in the detonator that has been described. Referring to this view, 55 indicates a firing pin, carried by the turret in a position about the same as that occupied by the cap 20 in the arrangement first described. The cap or primer that is arranged to be fired by this pin is designated 56 and is located at the inner end of the plug 47. Flash passages 57 lead from the 80 recess in which is located the cap 56 past or alongside of the firing pin 55 to the base of the chamber 18 in which is located the capsule carrying the detonating charge, so that when the cap is ignited the flame therefrom will fire the charge of black powder 21. 90

Some of the features of the detonator herein described, including the plunger adapted to be set back when the shell is fired from the gun, and the oscillating turret carried by the plunger and constituting a seat for the capsule that carries the detonating charge and is adapted to normally occupy a position of safety with the capsule out of line with the course it takes to the position where it detonates the booster charge, and is also adapted to move into position in line with that passage under the action of centrifugal force when the gun is fired, are shown and claimed in a co-pending application of mine filed July 27, 1915, Serial No. 42,134. I therefore have not herein described the construction of all the parts of the detonator here shown and the advantages inherent to them with that degree of particularity that I employed in my said other case, as that seems to be unnecessary.

What I claim is:—

1. In an impact detonator for projectiles 110 carrying a detonating charge, means for rendering the detonator safe should the said detonating charge accidentally explode, means for arming the detonator arranged to act only when the projectile is fired from a gun, means acting upon impact of the projectile for quickly firing the detonating charge, other means also acting upon impact of the projectile for causing a delayed firing of the detonating charge, and means for rendering one of the said firing means inoperative at will.

2. In an impact detonator for projectiles carrying a detonating charge, means acting upon impact of the projectile for quickly 130

firing the detonating charge, other means also acting upon impact of the projectile for causing a delayed firing of the detonating charge, means for rendering the quick firing means inoperative at will without disturbing the delay firing means and means for normally holding both the quick and delay firing means in nonfunctioning positions, arranged to operate to bring the 16 said firing means into functioning relations only upon the projectile carrying the fuse being fired from a gun.

3. In an impact detonator for projectiles carrying a detonating charge, means acting 15 upon impact of the projectile arranged to quickly fire the detonating charge, other means also acting upon impact of the projectile for causing a delayed firing of the detonating charge, the quick firing means 20 comprising a longitudinally movable firing pin that normally occupies a retracted position with its point shielded so that it can not act, and means under the control of the gunner for setting the said firing pin either 25 into projected firing position or retracted inactive position.

4. In an impact detonator for projectiles carrying a detonating charge, a plunger movable within the detonator, a firing pin 30 movable with reference to the plunger and acting upon impact of the projectile and the forward movement of the plunger due to such impact, to cause quick firing of the detonating charge, a firing rim also acting 35 upon impact and the forward movement of the plunger to cause a delayed firing of the detonating charge, and means under the control of the gunner for setting the firing pin either into active or inactive position.

40 5. In an impact detonator for projectiles, a firing pin arranged to act upon impact of the projectile, a plunger carrying the said pin, a spring for normally holding the 45 plunger in position so that the firing pin is inactive, and a member adjustable at the will of the gunner for positively moving the plunger against the action of the spring to cause the firing pin to assume active position 50 before the projectile is fired.

6. In an impact detonator for projectiles, a firing pin arranged to act upon impact of the projectile, a plunger carrying the said pin, a spring for normally holding the plunger 55 in position so that the firing pin is in inactive, nonfunctioning position, a member adjustable at the will of the gunner for positively moving the pin-carrying plunger against the action of its spring to cause the 60 pin to assume active, firing position before the projectile is fired, and means for normally maintaining the fuse in safe, non-firing condition arranged to function and arm the fuse only upon the projectile carrying it being fired from a gun.

7. In an impact detonator carrying a detonating charge, a primer arranged to cause quick firing of the detonating charge, another primer for causing a delayed firing of the charge, an adjustable firing pin for 70 acting upon impact of the projectile to fire the quick acting primer, other nonadjustable firing means acting immediately upon impact of the projectile for firing the delayed action primer, means under the control of the gunner for rendering the said adjustable firing pin inoperable at will and means for normally maintaining the fuse in safe, non-firing condition arranged to function and arm the fuse only upon the projectile carrying it being fired from a gun. 75

8. In an impact detonator for projectiles carrying a detonating charge, means for maintaining the parts of the detonator normally in safety positions, means acting upon 80 impact of the projectile for quickly firing the detonating charge, other means also acting upon impact of the projectile for causing a delayed firing of the detonating charge, the said firing means comprising 85 parts that are separated and inactive for firing when the parts of the detonator are in safety positions, means for arming the detonator and causing the firing means to assume functioning positions, arranged to 90 act only when the projectile is fired from the gun, and means for rendering the quick firing means totally inoperative at will.

9. A nose impact detonator arranged to be applied to a projectile carrying a charge 100 of high explosive, comprising a booster charge of explosive, a detonating charge of explosive, a movable capsule containing the detonating charge, a movable carrier in which the said capsule is placed, a runway 105 along which the capsule is adapted to travel extending from the said carrier into the booster charge, means for positively holding the said carrier in safety position with the capsule out of line with the said runway, the carrier being constructed and supported so that when free it will move, under the action of centrifugal force, into position with the capsule in line with the runway, means acting only when the projectile is 110 fired from a gun for freeing the said carrier and permitting it to move, a power charge for impelling the capsule from its seat and along the runway, means acting upon impact of the projectile for quickly firing the 115 said powder charge, other means acting upon impact of the projectile for causing a delayed firing of the said powder charge, and means for rendering one of the said impact firing means inoperative at will.

10. An impact detonator for a projectile comprising a capsule loaded with a detonating charge, a runway along which the said detonating capsule is impelled to the position where it is to be fired, a plunger mov- 120 125 130

- able in the detonator and arranged to set back when the projectile is fired from a gun and to set forward when the projectile strikes, the said plunger being perforated 5 in line with the runway for the passage of the said capsule, a carrier for the said capsule supported in the said plunger and free to move from a normal safety position with the capsule out of line with the said runway 10 to an arming position with the capsule in line therewith, means for normally holding the carrier in said safety position and arranged to be operated to release the carrier only upon the projectile being fired 15 from a gun, and means caused to operate when the plunger sets forward upon the projectile striking to impel the capsule along the said runway.
11. An impact detonator for a projectile, 20 comprising a partition centrally perforated and dividing the detonator into two chambers, in one of which is located a booster charge, a plunger located in the other chamber, the plunger being perforated in line 25 with the perforation through the said partition, a runway tube extending from the said partition into the midst of the booster charge and arranged in line with the perforations in the plunger and the partition.
- 30 a capsule loaded with a detonating charge adapted to be impelled through the said perforations and along the runway into the midst of the booster charge where it is to be fired, a carrier for the said capsule supported in the plunger and free to move from a normal safety position with the capsule out of line with the runway to an arming position with the capsule in line therewith, means for normally holding the carrier in 35 a safety position and arranged to be operated to release the carrier only upon the projectile being fired from a gun, and means caused to operate when the projectile strikes to impel the capsule along the runway.
- 40 12. An impact detonator for a projectile, comprising a partition centrally perforated and dividing the detonator into two chambers, in one of which is located a booster charge, a plunger located in the other chamber, being arranged to set back when the projectile is fired from a gun and to set forward when the projectile strikes, the plunger being perforated in line with the perforation through the said partition, a runway tube extending from the said partition into the midst of the booster charge and arranged in line with the perforations in the plunger and the partition, a capsule loaded with a detonating charge adapted to be impelled through 45 the said perforations and along the runway.
- 50 13. A nose impact detonator for a projectile comprising a main supporting piece in which is formed a central chamber, a booster charge located in rear of the said central chamber, a runway leading into the midst of the booster charge, a plunger located in the said central chamber and perforated in line of the said runway, an oscillating turret supported in the said plunger, the turret being formed with a seat for a capsule containing a detonating charge, the turret being freely movable from a normal safety position with the capsule which it carries out of line with the said runway to an arming position with the capsule in 55 line therewith, means for normally holding the carrier in the said safety position and arranged to be operated to release the carrier only upon the projectile being fired from a gun, and firing means arranged to cause the capsule to be impelled from its seat and into the runway arranged to be operated when the plunger sets forward upon the projectile striking.
- 60 14. In an impact detonator for ordnance projectiles, the combination of a container for a booster charge, a carrier for a detonating charge of sensitive explosive adapted to fire the booster charge, means separating these two explosive charges but having a 65 communicating passage between them, a movable support for the carrier containing the detonating charge adapted either to be moved into safety position with the detonating charge cut off from the booster charge, or to armed position with the detonating charge in line with the passage communicating with the booster charge, means for holding the said support locked in safety position arranged to release the carrier upon the projectile being fired from a gun, and means for positively locking the said support against movement when it comes to armed position.

CHARLES P. WATSON.
